ARTICLE STERILIZING DEVICE

Mack M. Werner, Brooklyn, N. Y.

Application May 4, 1939, Serial No. 271,674

7 Claims. (Cl. 21—84)

The invention relates to new and useful improvements in sterilizing and sterilized storing means, and more particularly to such improvements in portable, collapsible heating and storing devices for sterilizing hypodermic syringes, needles and instruments in boiling liquid and for storing and protecting the instruments or contents of the sterilizer in a sterilized state.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a vertical, longitudinal section through a device embodying the invention showing the device in sterilized position;

Fig. 2 is an end view but showing the device in closed or collapsed position;

Fig. 3 is a fragmentary detail on line 3—3 of Fig. 1;

Fig. 4 is a horizontal section on line 4—4 of Fig. 1;

Fig. 5 is a horizontal section on line 5—5 of Fig. 1;

Fig. 6 is a fragmentary, vertical section, corresponding to the left-hand end of Fig. 1 but showing the parts in closed or collapsed position;

Fig. 7 is a front elevation, with parts broken away of a modified form of the invention;

Fig. 8 is a front elevation of the cover and drainage tray shown in Fig. 7; and

Fig. 9 is a section on line 9—9 of Fig. 8.

Objects of the invention are to provide a portable, compact and simple device for sterilizing hypodermic needles, syringes and small medical instruments and storing them in protected sterilized condition ready for instantaneous use; to provide such a device wherein a needle or needles and the disassembled plungers and barrels of hypodermic syringes may be placed in liquid in a chamber, the liquid quickly heated, thereby sterilizing the hypodermic articles, the sterilizing liquid drained off and the sterilized articles retained in the chamber, the sterilized condition being re-

tained and protected, with the devices ready for instantaneous use on simply opening the chamber; to provide a device of the character described which is of simple structure, and is rendered exceedingly compact and portable by reason of certain parts being extensible and collapsible between a closed or packed position and an operating or sterilizing position. To these ends a shallow, elongated chamber for holding heating fluid and having wick-holding means, and a superposed elongated chamber for holding a sterilizing fluid are slidable between a position in contact with each other and a spaced-apart position in which the flame heats the sterilizing liquid. The sterilizing chamber has a drain for drawing off the liquid after sterilization, a lid giving access to the top of the chamber and devices for clamping the lid substantially sealed, so as to protect the sterilized hypodermic devices within. The foregoing general description and the following detailed description as well are exemplary and explanatory but are not restrictive of the invention.

Referring now in detail to the embodiment of the invention illustrated by way of example in the accompanying drawings, a chamber is provided for holding the heating fluid, said chamber being of shallow, elongated, and preferably of flat, rectangular form serving as a base for the device. This chamber has a bottom 1, side walls 2 and 3, end walls 5 and 6, and a flat top 4. The bottom 1 has a turned-down edge adjoining the sides to provide support along the side edges. Centrally of the top plate 4 of this chamber and recessed below the plane thereof is a wick-supporting device 8, holding the wick w in position to create a heating flame f when the sterilizing fluid is being heated. A screw cap 9 encloses the wick and seals the chamber when the flame is not burning. A plug 9' is screw-threaded into a fuel-supplying opening.

The chamber for holding the sterilizing liquid and for storing the sterilized instruments is likewise an elongated chamber 10, preferably rectangular, is supported from and above the heating liquid chamber, is movable into contact therewith for packing in the inoperative position, and is maintained in spaced-apart position above the flame during the heating and sterilizing operation. Said chamber comprises a flat bottom plate 11, side walls 12 and 13, and end walls 14 and 15. The top of the chamber is a lid 18, hinged to the side 13 by hinges 1. The lid has on its under side, and extending all the way around just within its edges a turned-over metal lip 21, adapted to fit tightly within the turned-over up-

per edges of the side walls and end walls of the chamber, making in effect an airtight seal. Means are provided for clamping the lid 18 in closed position to guard against accidental opening thereof whereby the sterilized condition of contained devices might be impaired or destroyed. As embodied, at either end of the chamber a looped bail or hook 24 of stiff wire is pivotally mounted at 25 in a pivot plate 26, 10 which plate is fastened to the side wall of the chamber. These bails or hooks are movable between the broken-line, withdrawn positions and the full line, clamping positions in Fig. 1.

Means are provided for drawing off the heated sterilizing fluid after sterilization has been effected, and for this purpose a screw-plug 31 is screw threaded into the side wall 15 of the sterilizing chamber close to the bottom of the chamber. This plug has within it an angled aperture 32, and when the plug is screwed outwardly the liquid will drain off through this passage, but when the plug is screwed home it provides an airtight seal. The drainage opening 32 is so small as to practically obviate danger of infection to 25 the devices in the chamber during drainage. Further, sterilization will be maintained during drainage due to the presence of hot steam and vapor in the chamber. Thus the sterilized device may be kept in the chamber after boiling, 30 remaining practically indefinitely in a sterilized condition after the water is drawn off. Preferably the devices to be sterilized are wrapped in gauze in the chamber to facilitate handling and sterile removal. This feature of the invention 35 enables the user to boil articles at his convenience and transport them in sterile condition ready for immediate use.

The embodied form of supporting means for the sterilizing chamber, which permits the expanding and collapsible action, comprises cylindrical rods 34 and 35 which are fastened to the top plate 4 of the heating fluid chamber, and extend upwardly therefrom. These rods extend within two closed tubes 38 and 39, conveniently 40 located within the sterilizing chamber. Automatically operating devices are provided whereby when the two chambers are drawn apart they will be positioned in the heating and sterilizing position, and by merely pushing them together, 45 they will move into contact in the collapsed or packed position. As embodied, this device comprises a notch 41 formed in the upper part of each of the rods 34 and 35 (Figs. 1, 3 and 6) with which cooperates an inwardly-bent and upwardly-extending resilient tongue 42, formed in the inner side of the corresponding tube 38 or 39. When the sterilizing chamber is pushed upwardly these tongues will snap into the notches and will hold the chamber in the elevated position, but when the device is pushed together these tongues will yield and permit the device to close.

A skirting plate 45 is fixed to and extends downwardly from the bottoms of the side walls 65 and end walls of the sterilizing chamber, and serves to retain the hot gases against the bottom plate 11 of the chamber to conserve the heat and expedite the heating. A corresponding flange 46 is fixed to and extends upwardly 70 from the top edges of the side walls and end walls of the heating fluid chamber, and when the two chambers are pushed together, the skirt 45 and the flange 46 constitute a box-lid closure (Fig. 6), entirely closing the device and 75 holding the parts firmly together. The flange 46

is positioned to permit the tubes 38 and 39 to close down as shown in Fig. 6.

In Figs. 7, 8 and 9 is shown a modification in which means are provided for removing sterilized articles from the hot water in chamber 10 without requiring the user to put his fingers or instruments into the water. As embodied, the chamber 10 is provided with a removable cover or lid 50 which is not hinged to the chamber but is adapted to be lifted bodily away therefrom as 10 by a handle or bail 51 pivotally connected to the lid by a stud 52. The lid 50 may be tightly sealed to the top of the chamber while in use by the fastening bails or latches 24 heretofore described. A supplementary drainage tray 55 is 15 attached to the inner surface of the lid by suspending chains 56 which are preferably attached, one at each corner of the rectangular tray 55. The length of the chains is such that when the lid 50 is in place, the bottom of the tray rests 20 loosely on the bottom 11 of the chamber 10.

The bottom 57 of tray 56 is perforated, preferably throughout, so that it will settle through the water in the chamber and may be easily lifted from the bottom when the lid 50 is elevated. Thereby articles, such as hypodermic syringe parts, may be taken from the boiling water merely by lifting the cover 50 and raising the tray above the level of the water. If desired, the tray may be provided with one or more 30 spring clips 58 for the purpose of holding syringe plungers, barrels, needle hubs, and the like.

It will be understood that the above-described modification is useable with the device as shown and described in connection with Figs. 1 to 6, 35 said modification being particularly helpful where the sterilized articles are to be removed from the hot water at once, as when it is not convenient to drain out the water through the aperture 32. It is also an added convenience in 40 introducing the articles to be sterilized into the tank of water.

If desired, a perforated tray may also be attached to the form of lid shown in Figs. 1 and 2, in which case the inner perforate tray is hinged 45 to the lid so that when the lid is closed the tray and contents are immersed in the water, while raising the lid causes the tray to rise above the liquid level within the chamber 10.

The invention in its broader aspects is not limited to the specific mechanisms shown and described but departures may be made therefrom within the scope of the accompanying claims 55 without departing from the principles of the invention and without sacrificing its chief advantages.

What I claim is:

1. An extensible and collapsible sterilizing and 60 sterilized storage device comprising a chamber for holding a sterilizing liquid in which an article is immersed, a chamber for holding a heating fluid and having flame producing means, means for moving said chambers toward and from each 65 other between a collapsed storage position and a spaced-apart liquid heating position, means for drawing the heated liquid from the liquid-holding chamber after sterilization and means for tightly closing the liquid holding chamber 70 to maintain an enclosed article in sterilized condition.

2. An extensible and collapsible sterilizing and sterilized storage device comprising a chamber for holding a sterilizing liquid in which an arti- 75

cle is immersed, a chamber for holding a heating fluid and having flame producing means, a heat-retaining flange extending downwardly about the bottom of said sterilizing chamber, means for moving said chambers toward and from each other between a collapsed storage position and a spaced-apart liquid heating position, means for drawing the heated liquid from the liquid-holding chamber after sterilization and means for tightly closing the liquid holding chamber to maintain an enclosed article in sterilized condition.

3. An extensible and collapsible sterilizing and sterilized storage device comprising a chamber for holding a sterilizing liquid in which an article is immersed, a chamber for holding a heating fluid and having flame producing means, a heat-retaining flange extending downwardly about the bottom of said sterilizing chamber, means for moving said chambers toward and from each other between a collapsed storage position and a spaced-apart liquid heating position, means for drawing the heated liquid from the liquid-holding chamber after sterilization and means for tightly closing the liquid holding chamber to maintain an enclosed article in sterilized condition, a flange extending upwardly about the top of said heating fluid chamber, one of said flanges nesting closely within the other to hold the two chambers firmly together when in the collapsed storage position.

4. An extensible and collapsible sterilizing and sterilized storage device comprising a flat shallow chamber for holding heating fluid and having wick-holding means in its upper surface, supports fixed to and extending upwardly from said heating fluid chamber, a chamber for holding a sterilizing fluid in which a needle is immersed, means for movably supporting said sterilizing chamber on said supports permitting the chamber to be moved together into packing position or moved apart into sterilizing position, means for drawing the heated fluid from said sterilizing chamber after sterilization, a lid for said sterilizing chamber and means for clamping down the lid to maintain the chamber closed to protect an enclosed needle in sterilized condition.

5. An extensible and collapsible sterilizing and sterilized storage device for hypodermic needles comprising a flat shallow chamber for holding heating fluid and having wick-holding means in its upper surface, a chamber for holding a sterilizing fluid in which a needle is immersed, means for permanently connecting said chambers and having reciprocable members for permitting the chambers to be closed together for storage or spaced apart for heating, means for drawing the heated fluid from said sterilizing chamber after sterilization, a lid for said sterilizing chamber and means for clamping down the lid to maintain the chamber closed to protect an enclosed needle in sterilized condition.

ilizing fluid in which a needle is immersed, means for drawing the heated fluid from said sterilizing chamber after sterilization, a lid for said sterilizing chamber and means for clamping down the lid to maintain the chamber closed to protect an enclosed needle in sterilized condition.

6. An extensible and collapsible sterilizing and sterilized storage device for hypodermic needles comprising a flat shallow chamber for holding heating fluid and having wick-holding means in its upper surface, supports fixed to and extending upwardly from said heating fluid chamber, a chamber for holding a sterilizing fluid in which a needle is immersed, means for movably supporting said sterilizing chamber on said supports permitting the chamber to be moved into packing position or moved apart into sterilizing position, means for maintaining said sterilizing chamber in said spaced relationship, a downwardly extending heat-retaining flange on the bottom of said sterilizing chamber, means for drawing the heated liquid from the sterilizing chamber after sterilization and means for tightly closing the sterilizing chamber to maintain an enclosed needle in sterilized condition.

7. An extensible and collapsible sterilizing and sterilized storage device for hypodermic needles comprising a flat shallow chamber for holding heating fluid and having wick-holding means in its upper surface, a chamber for holding a sterilizing fluid in which a needle is immersed, means for permanently connecting said chambers and having reciprocable members for permitting the chambers to be closed together for storage or spaced apart for heating, means for maintaining said sterilizing chamber in said spaced relationship, a downwardly extending heat-retaining flange on the bottom of said sterilizing chamber, means for drawing the heated liquid from the sterilizing chamber after sterilization and means for tightly closing the sterilizing chamber to maintain an enclosed needle in sterilized condition, said closing means having movably connected thereto a foraminous member for holding the needles in the liquid during heating and to withdraw them from the liquid when the sterilizing chamber is opened.

MACK M. WERNER.
